UNITED STATES PATENT OFFICE.

ROBERT E. YOLTON, OF BIRMINGHAM, ALABAMA, ASSIGNOR TO KILBY FROG & SWITCH COMPANY, A CORPORATION OF ALABAMA.

SWITCH-THROW MECHANISM.

Application filed March 30, 1925. Serial No. 19,203.

To all whom it may concern:

Be it known that I, ROBERT E. YOLTON, a citizen of the United States of America, residing at Birmingham, in the county of Jefferson and State of Alabama, have invented certain new and useful Improvements in Switch-Throw Mechanism, of which the following is a specification.

My invention relates to a switch operating mechanism, and particularly to what is known as parallel throw mechanism for operating a switch in which the actuating lever moves in a plane parallel with the track and at right angles to the switch throw rod which it actuates to move the switch.

My present invention is applicable to switch stands or any standard type of switch operating mechanism and is distinguished by the provision of a cylinder and slide block as a means for converting the parallel motion of the lever into the transverse motion imparted to the throw rod. The special advantages of this arrangement is that I obtain a full bearing for actuating the switch throughout the entire travel of the lever and thus avoid what may be termed a point bearing which is present in most parallel throw switch mechanism and which gives a point of high resistance to the operation of the lever. In my arrangement I avoid all lost-motion in the connections and reduce the friction to a minimum so that the switch can be thrown with the greatest ease.

My invention further contemplates providing the throw lever with a pin adapted to engage a piston working in a cylinder on a bell crank element to which the throw rod is connected, the cylinder being preferably open overhead and in its side so that the top of the piston will rise above the top of the cylinder and will drop below the side opening therein during each operation, thus enabling the piston to keep the cylinder clear of obstructions, cinders, etc., that might otherwise tend to accumulate therein.

My invention further comprises the novel details of construction and arrangements of parts, which in their preferred embodiment only are hereinafter more particularly described, reference being had to the accompanying drawings which form a part of this specification, and in which:

Fig. 1 is a plan view of the switch stand.

Fig. 2 is a side elevation of Fig. 1.

Fig. 3 is an enlarged perspective view of the bell crank casting with the cylinder and piston.

Similar reference numerals refer to similar parts throughout the drawings.

I have illustrated my invention in its simplest form, but it is obvious that the principles of construction are readily adaptable to various other types of switch operating mechanism, including switch stands. As shown, the mechanism comprises a base 1 having notches 2 to receive the spikes by which it is anchored to the cross ties alongside the track. The base is formed with a perforated ear 3 that receives a pin 4 on the handle 5. A cotter key 6 secures the pin in the ear and thus the handle is pivotally mounted on the base in position to swing in a plane parallel to the track. The handle carries at its free end a weight 7 provided with a grip for its convenient operation. At an intermediate point, near its pivot end and projecting on the opposite side from the pin 6, the handle carries an operating pin 8. This pin is adapted to enter a side opening 9 drilled in a piston 10, which piston is mounted for vertical play in a cylinder 11 formed at one end of the arm 12 of a crank lever, which lever is pivoted to an extension 13 of the base by means of a vertical stud or pin 14. The other arm 15 of the bell crank is provided with a flattened base 16 adapted to slide on an extension 13 of the base casting and having a threaded hole bored longitudinally and horizontally therethrough to receive an eye bolt 17 to which the connecting rod, not shown, for throwing the switch is adapted to be connected. This eye bolt can be screwed in or out to vary the length of the motion imparted to the throw rod and in order that a maximum adjustment may be obtained the hole is bored high enough in and entirely through the arm 15 so that the inner end of the eye bolt will pass clear above the pivot pin 14, thus giving a maximum range of adjustment with a relatively short arm 15. The cylinder 10 has its top edge bevelled to prevent the collection of cinders and dirt thereon and it is provided with a large side aperture 18 which rises above the height of the piston when the latter is in its lowermost position.

2
By referring to Fig. 3, it will be observed that when the piston reaches its highest position, which is when the handle is vertical, its upper edge will rise above the top 5 of the cylinder:

In operation, having mounted the base and connected the eye bolt to the switch throw rod, assuming the handle in the position shown in Fig. 1, on grasping and raising the handle the pin 8 will be caused to travel through an arcuate path about the pin 4 as an axis and in following this path it will act both to lift the piston in the cylinder and to force the piston in the direction of motion of the handle, thus causing the cylinder to move from full to dotted line position, as shown in Fig. 1, and thus operating the switch. Throughout the entire operation there is no lost-motion and the 10 handle is constantly and continually exerting pressure against the bell crank lever to throw the latter with as nearly a constant load as possible.

Though I have described with great particularity the details of the embodiment of the invention as shown, it is not to be construed that I am limited thereto, as changes in arrangement and substitution of equivalents may be made by those skilled in the 25 art without departing from the invention as defined in the appended claims.

Having thus described my invention, what I claim as new and desire to secure by Letters Patent, is:—

35 1. A switch throw mechanism comprising a stand, a lever mounted on said stand for movement parallel with the track, a horizontally movable rocker mounted on the stand and having one end adapted for connection to the switch and the other end carrying an upright cylinder, a piston in 40 said cylinder, and an operating connection from the lever to the piston, there being

a slot in the cylinder through which said connection is free to move with the lever. 45

2. A parallel switch throw mechanism comprising a switch operating rocker element pivoted to move in a horizontal plane, a lever movable through a vertical plane, an operating connection between the lever and the rocker element comprising an upright cylinder having a side aperture, a piston reciprocable in said cylinder, and a pin connecting the piston and lever through said aperture. 50

3. A parallel switch throw mechanism in accordance with claim 2, in which the cylinder is left open overhead and the piston is adapted to rise above the top of the cylinder with each operation, the top of the cylinder being bevelled outwardly and downwardly. 55

4. A parallel switch throw mechanism in accordance with claim 2, in which the aperture overhead is shaped to follow the path of the piston operating connection on the lever, and the piston when in its lowermost position is adapted to drop below the top level of said aperture. 60

5. A parallel switch throw mechanism 70 comprising a stand, a lever pivoted to the stand to swing in a vertical plane parallel with the track, a bell crank lever pivoted to the stand to swing in a horizontal plane, a vertical cylinder on one arm of the bell 75 crank, there being a vertically elongated slot in the outer side of said cylinder, a piston movable with a snug fit in said cylinder, a pin on the lever, a side hole in the piston adapted to receive said pin with a snug fit, 80 and an element adjustably mounted on the other arm of the bell crank lever and adapted to receive the switch throw connection.

In testimony whereof I affix my signature.

ROBERT E. YOLTON.
